UNITED STATES PATENT OFFICE.

ERIK A. EKEDAHL AND ERICK G. SAMPSON, OF JAMESTOWN, NEW YORK, ASSIGNORS TO ART METAL CONSTRUCTION COMPANY, OF JAMESTOWN, NEW YORK, A CORPORATION OF NEW YORK.

DRAWER FOR CABINETS, &c.

No. 884,476.

Specification of Letters Patent. Patented April 14, 1908.

Application filed November 30, 1907. Serial No. 404,520.

To all whom it may concern:

Be it known that we, ERIK A. EKEDAHL and ERICK G. SAMPSON, residents of Jamestown, in the county of Chautauqua and State of New York, have invented a new and useful Improvement in Drawers for Cabinets, &c.; and we do hereby declare the following to be a full, clear, and exact description thereof.

10 Our invention relates to drawers for cabinets, filing cases, etc. and more particularly to a suspension device for such drawers, whereby the drawer may be drawn out and held in horizontal position, its outward movement being so limited as to prevent its accidentally dropping when drawn out to its full length.

15 The objects of our invention are to provide for the free movement of the drawer so as to 20 reduce the amount of friction while at the same time to simplify the construction by doing away with rollers mounted on studs which may in time wear out or work loose.

25 Our invention comprises the novel features hereinafter set forth and claimed.

In the accompanying drawings Figure 1 is a vertical section of the upper part of the cabinet with a drawer in elevation partly drawn from the cabinet, the dotted lines 30 showing the drawer pulled out full length and in position to be detached from the cabinet; Fig. 2 is a detail showing the drawer removed; Fig. 3 is a cross section on the line 3—3, Fig. 1; Fig. 4 is a cross section on the line 4—4, Fig. 1; and Figs. 5 and 6 are details.

35 In the drawing the numeral 2 designates a portion of a cabinet or filing case provided with drawers 3. Secured to the inner walls 40 of the casing are the guide strips 4. These guide strips may be formed of metal flanged and bent to form the guide strip illustrated. The guide strips 4 are provided with the flanges 5 having openings 6 through which 45 the rivets, bolts or other connecting devices pass to secure the guide strip in position on the inner wall of the casing. The guide strip 4 is provided with the upper inwardly extending flange 7 which forms a guide-way 8. 50 At the inner end of the guide-way 8 is the buffer 9 which may be formed of leather or other suitable material. Within the guide-way 8 are the studs or stops 10 which control the movement of the unattached roller 11

which is adapted to move freely within the 55 guide-way 8 between the studs 10. At the forward end of the guide strips 4 are the guide-ways 12 within which are the unattached rollers 13. The movement of the rollers 13 is controlled by the stud 10 at one 60 end and at its opposite end by the inwardly extending flange 14 to which the buffer 15 is secured. The guide strip is also provided with the end flange 16 riveted or otherwise secured to the casing 2. Upper guide strips 65 17 are secured to the inner walls of the casing.

The suspension frame 18 is adapted to move back and forth in the guide strips 4 and 17 and said suspension frame consists of the 70 side bars 19 which may be formed of sheet metal bent to suitable shape. These side bars 19 have the upwardly extending flanges 20 forming guide-ways 21 for the reception of the unattached rollers 22. Within the guide-way 21 at suitable intervals are secured the stops 23 which control the movement of the rollers 22. At the rear of the guide-ways 21 are the buffers 24. The side bars 19 are connected at their rear ends by the cross bars 25 80 having the elongated openings 26 through which the bolt 27 passes to secure said cross bars together to form the suspension frame. The side bars 19 are also provided with the inwardly extending flanges 28 along the upper 85 edge. Stop blocks 29 are secured to the outer ends of the side bars 19, said stop blocks having the inclined faces 30.

Secured to the side bars 19 are the plates 31 which extend below said side bars and 90 said plates have the inwardly extending flanges 32 with stops 33 at each end thereof. These flanges 32 enter the guide-way 8 of the guide strips 4, and the rollers 11 move along the flanges 32 and 7, while the side bars rest 95 on the rollers 13. The inner ends of said plates 31 are adapted to move into contact with the buffers 9.

Secured to the outside walls of the drawer 34 are the strips 35. These strips 35 are cut 100 or slit longitudinally as at 36 at intervals and the metal above such slits is bowed or bent, as at 37. The rivets or bolts 38 passing through the bowed portions 37 secure said strips to the drawers 34. By this construction 105 the lower edges of the strips 35 are sufficiently removed from the walls of the drawers to permit of their engagement with the guide-

ways 21 of the side bars 19 without the use of separate spacing pieces along the upper edges of said strips. The inner ends of the strips 35 are provided with up-turned ends 39.

5 When said strips 35 are inserted in the guide-ways 21 of the side bars 19 the lower edges of said strips rest on the rollers 22.

Secured to the outer walls of the drawers 34 are the stop blocks 40 which have the 10 lower inclined faces 41.

In withdrawing the drawer the side strips 35 of the drawer move freely within the guide-ways 21 on the unattached rollers 22. These loose or unattached rollers are what 15 might be termed self-placing rollers in that they do not require any manipulation when the drawer is replaced after being taken from the case, but automatically assume their positions without any attention on the part 20 of the person inserting the drawer. At the same time the side bars 19 slide freely within the guide-ways 8 and 12, said side bars resting upon the rollers 13 while the rollers 11 take up the friction in the guide-ways 8 due 25 to the movement of the plates 31. The outward movement of the side bars 19 is limited by the studs 10 at the outer end of the guide-ways 8, for when the side bar is withdrawn to the full length the rollers 11 will be held between the studs 10 at the outer end of the 30 guide-ways 8 and the studs or stops 33 at the inner end of the plates 31, which prevents the further outward movement of the side bars 19. When the side bars 19 have reached the 35 limit of their outward movement the drawer is still free to move outward with its strips 35 moving in the guide-ways 21. The outward movement of the drawer is limited by the stop blocks 40 coming in contact with the 40 stop blocks 29 on the outer ends of the side bars 19. The drawer when withdrawn to its full length is held rigidly in a horizontal position and there is no danger of its tilting or dropping to the floor. If it is desired to re- 45 move the drawer entirely after it is withdrawn to its full extent, it is only necessary to lift the front end of the drawer sufficiently to allow the stop blocks 40 to clear the stop blocks 29 when the drawer may be withdrawn in a straight line until the side strips 50 35 have been completely withdrawn from the guide-ways 21 of the side bars 19. On the insertion of the drawer the inclined faces of the blocks 40 move up over the inclined faces 55 of the stops 29.

By our invention we provide a freely moving drawer in which the rollers are permitted to move at will within the guide-ways, thereby dispensing with the mounting of said 60 rollers on studs in fixed positions, which is objectionable as the studs are liable to wear out or work loose in their bearings. In the insertion of the drawer after it is withdrawn, no attention need be paid to the position of the rollers as they assume their positions

without any attention and they always move automatically to the place where they are most needed to reduce the friction.

What we claim is:

1. In a suspension device for drawers, the 70 combination with the case or cabinet, of guide-strips on the inner walls of same, said guide-strips having guide-ways therein, unattached rollers in said guide-ways, stops for said rollers therein, a suspension device, the 75 side bars of said device having downwardly extending portions entering said guide-ways, and a drawer slideable in said suspension device.

2. In a suspension device for drawers, the 80 combination with the case or cabinet of guide-strips having guide-ways therein, unattached rollers in said guide-ways, stops for said rollers therein, a suspension device, the side bars of said suspension device having 85 downwardly extending portions entering said guide-ways, unattached rollers in said guide-strips on which said side bars rest, and a drawer slideable on said suspension device.

3. In a suspension device for drawers, the 90 combination with the case or cabinet of guide-strips on the inner walls of same, said guide-strips having inwardly extending flanges along their upper edges for a portion of their length forming guide-ways, stops at 95 each end of said guide-ways, rollers in said guide-ways, a suspension device, side bars, plates on said side bars having flanges entering said guide-ways, stops on said plates, unattached rollers in said guide-strips upon 100 which said side bars rest, and a drawer slideable on said suspension device.

4. In a suspension device for drawers, the 105 combination with the case or cabinet of guide-strips on the inner walls of same, a suspension device slideable in said guide-strips, stops at the outer ends of said suspension device, unattached rollers carried by said suspension device, a drawer, strips on said drawer engaging said suspension device and 110 moving on said rollers, and stop blocks having inclined lower faces on said drawer.

5. In a suspension device for drawers, the combination with the case or cabinet, of guide-strips on the inner walls of the same, a 115 suspension device slideable in said guide-strips, inclined stops at the outer ends of said suspension device, unattached rollers carried by said suspension device, a drawer, strips on said drawer engaging said suspension device 120 and moving on said rollers, and stop blocks on said drawer having inclined lower faces.

6. In a suspension device for drawers, the combination with the case or cabinet of guide-strips on the inner walls of same, a sus- 125 pension device slideable in said guide-strips, a drawer, and strips on said drawer slideable in said suspension device, said strips having slits and bowed portions secured to said drawer.

7. In a suspension device for drawers, the combination with the case or cabinet, of guide strips on the inner walls of the same, a suspension device slideable on said guide strips, the side bars of said suspension device having upturned flanges forming guides, unattached rollers in said guides, and a drawer slideable on said rollers.

In testimony whereof, we the said ERIK A. EKEDAHL and ERICK G. SAMPSON have here- 10 unto set out hands.

ERIK A. EKEDAHL.
ERICK G. SAMPSON.
